No. 36,949.

Patented June 7, 1904.

UNITED STATES PATENT OFFICE.

GEORGE W. SHIEBLER, OF NEW YORK, N. Y.

DESIGN FOR A HANDLE FOR SPOONS, FORKS, OR SIMILAR ARTICLES.

SPECIFICATION forming part of Design No. 36,949, dated June 7, 1904.

Application filed May 6, 1904. Serial No. 206,761. Term of patent 7 years.

To all whom it may concern:

Be it known that I, GEORGE W. SHIEBLER, a citizen of the United States, residing at the borough of Brooklyn, in the county of Kings, city and State of New York, have invented a new, original, and ornamental Design for the Handle of a Spoon, Fork, or Similar Article, of which the following is a specification, reference being had to the accompanying drawings, forming part thereof.

Figure 1 is an obverse and Fig. 2 a reverse view.

I claim—

The ornamental design for the handle of a spoon, fork, or similar article, substantially as shown.

GEO. W. SHIEBLER.
